UNITED STATES PATENT OFFICE.

JAMES FRANKLIN BARBER, OF BROKEN ARROW, ALABAMA.

HARNESS.

SPECIFICATION forming part of Letters Patent No. 361,917, dated April 26, 1887.

Application filed December 4, 1886. Serial No. 220,725. (No model.)

To all whom it may concern:

Be it known that I, JAMES FRANKLIN BARBER, a citizen of the United States, residing at Broken Arrow, in the county of St. Clair and State of Alabama, have invented a new and useful Improvement in Harness, of which the following is a specification, reference being had to the accompanying drawings.

My invention relates to an improvement in harness; and it consists in the peculiar construction and combination of devices, that will be more fully set forth hereinafter, and particularly pointed out in the claims.

In the drawings, Figure 1 is a side elevation 15 of my harness complete. Fig. 2 is a similar view of the buckle for uniting the trace, the saddle-strap, and the breeching-strap. Fig. 3 is a horizontal longitudinal sectional view of the same, taken on the line xx of Fig. 2. Fig. 20 4 is a vertical sectional view taken on the line yy of Fig. 2.

A represents a combination-buckle, having the loop a , provided with a pivoted tongue, b , at its front end, the loop c , having the tongue d near its rear end, on the upper side, and the rearwardly extending loop e . Loops f and g are formed in the body of the buckle below the loop c , a cross-bar, h , being between said loops. An eye, i , projects from the face of 30 the cross-bar, and to this eye is secured a snap-hook, k .

It will be observed by reference to Fig. 3 that the body portion of the buckle is projected outwardly beyond the plane of the outer 35 portions of the loops a and c , and thereby the said projected body portion permits the free ends of the traces and of the breeching-straps to pass through the loops a and c and lie snugly against each other on the inner side of the body 40 portion, and thus avoid chafing the sides of the horse.

B represents the strap that depends from the harness-saddle, C the breeching, D the hip-strap, E the back-strap, and F the breeching-45 strap or holdback-strap, all of which are constructed in the usual way. The lower end of the strap B is secured by the tongue d in the loop c , and passed through the loops f and g back of the cross-bar. A ring, G, is slipped

on the thill z of the vehicle-back to a stop, z' , 50 depending from the lower side thereof, and to this ring is connected a link, H, adapted to be caught by the snap-hook to support the thills. A rod or wire, I, is secured at its front end to the link H, and at its rear end to the single-tree z'' . The breeching-strap is secured in the loop e , and the short trace K, which has its front end secured to the hames in the usual manner, is secured at its rear end to the loop a by the tongue b . 55

I have herein shown and described only one side of the harness; but the other side will of course be a counterpart thereof.

It will be readily seen that the horse is attached to the thills of the vehicle only by the 65 snap-hooks k , and that in order to detach the horse from the vehicle it is only necessary to detach the snap-hooks from the links H. The rings G, links H, and rods I are permanently attached to the thills and remain on 70 them when the horse is taken out. Should it be desired to remove them from the thills for any reason, it is only necessary in order to do so to release the rods I from the ends of the single-tree and slip the rings forward off the 75 thills.

A harness thus constructed is light, cheap, and very durable, can be easily and quickly placed on the horse, and enables the latter to be attached to or detached from the thills in a 80 moment, which is a very great convenience in cold weather or when in a hurry.

Having thus described my invention, I claim—

1. In a harness, the combination of the 85 buckles A, uniting the breeching-straps, traces, and back-band, and having the eyes i , with the snap-hook attached to the said eyes and adapted to engage suitable rings or keepers on the thills of the vehicle, substantially as described.

2. The combination of the harness having the buckles A, for uniting the saddle-straps, traces, and breeching-straps, and the hooks k , attached to the said buckles, with the thills 95 having the rings G and the draft-rods I, substantially as described.

3. The combination, with the buckle, of the

ring G on the vehicle-thill, connected to the buckle, and the strap K, connecting the buckle and the horse-collar, substantially as set forth.

4. The buckle having the loops *a c*, provided with tongues *b d*, and the loop *e* and the hook *k*, loosely connected to the buckle, as set forth.

In testimony that I claim the foregoing as my own I have hereto affixed my signature in presence of two witnesses.

JAMES FRANKLIN BARBER.
